UNITED STATES PATENT OFFICE

JOHN FIELDING, OF NORTH PROVIDENCE, RHODE ISLAND, ASSIGNOR OF ONE-HALF TO
JOSEPH P. WHITAKER, OF APPONAUG, RHODE ISLAND

MEANS FOR SECURING A METALLIC BRIDGE TO NONMETALLIC LENS RIMS

Application filed April 8, 1931. Serial No. 528,613.

This invention relates to an ophthalmic mounting and has for its object to connect a pair of non-metallic lens rims together by a resilient bridge of hardened metal stock.

5 Another object of the invention is the use of a high quality spring for attaching lens rims together.

A further object of the invention is the provision of a construction which may be 10 made more inexpensively than other constructions which utilize portions of the resilient bridge member for attaching purposes, and to provide a stronger and more secure means for holding the parts together.

15 A still further object of the invention is to improve the appearance of the connection between the parts that the same may have a more ornamental effect when worn.

With these and other objects in view, the 20 invention consists of certain novel features of construction, as will be more fully described, and particularly pointed out in the appended claims.

In the accompanying drawing:

25 Fig. 1 is a face view of the lens rims connected together by the bridge;

Fig. 2 is a top edge view thereof;

Fig. 3 is a perspective view of the bridge alone;

30 Fig. 4 is a perspective view of the connecting member alone;

Fig. 5 is a section on line 5—5 of Figure 4;

Fig. 6 is a section on line 6—6 of Figure 5;

Fig. 7 is a section on line 7—7 of Figure 1.

35 It has been usual to connect non-metallic lens rims together where elasticity is required in the bridge piece by a piece of resilient stock which is sufficiently soft to permit bending, such soft stock, however, easily ac-

40 quires a set and is not that which is desired for best elastic or resilient action; it, however, is impractical to use a high grade spring stock because of the breaking and weakening thereof if folded about the rims

45 for securing the spring thereto, and in order that the highest grade hard spring stock may be used and also a more ductile connection, I have provided means by which these parts may be formed separately and connected together without the use of heat or

solder which will anneal the spring stock. I have found that in this way the parts may be more inexpensively formed and assembled together, thereby making a saving throughout in manufacture, and further providing a 55 structure which will be of better appearance and more satisfactory to the user; and the following is a detailed description of the present embodiment of this invention, illustrating the preferred means by which these advantageous results may be accomplished.

With reference to the drawing, 10 designates the lenses with a non-metallic rim 11 encircling the same formed of celluloid, zylonite or similar material. The bridge 65 member 12 is formed of flat stock of relatively hard springy nature with notches 13, 14 on opposite sides in the edges thereof adjacent each end.

Connecting members illustrated generally 70 at 15, each have a top wall 16 and side flanges 17, with the top wall 16 raised to form a pocket 18 which is indented as at 19 to provide projections 20 on the inner surface of the pocket 18. The pocket receives the end of the bridge 12 with the projections 20 extending into the recesses 75 13 and 14, and the end 21 of the bridge abutting the end 22 of the pocket to assist in holding the same securely therein.

80 The pocket 20 is of a depth substantially the thickness of the bridge 12, and in attaching the same to the rim, the bridge is placed in the pocket, and the connecting member 15 laid upon the rim at the desired location, after which the flanges 17 are folded about the non-metallic rim to snugly embrace the same and firmly secure the bridge 85 in position.

90 In this manner, the hardened spring stock is secured to the non-metallic rims without the use of solder, and the same may be formed of the highest grade spring stock desired without fear of cracking or breaking the same by folding for securing the same to the rim. Further, the appearance of a construction so formed is an improvement over prior formations, and the pocket and shape thereof assist to ornament the 100

connecting member which attaches the bridge to the frame.

The spring bridge used is of a degree of hardness and flexibility to permit one lens rim to fold or be moved over the other for more compact storage of the parts and thus it will be apparent that a set may occur in the bridge if it were soldered or heated and thus annealed at the point of heat treating, which setting is eliminated in my construction by which perfect elasticity is obtained of the spring bridge throughout its length.

While I have described certain construction forms which embody the principles of my invention, it is obvious that other desired changes in arrangement, may be made within the spirit and the scope of the invention as defined in the appended claims.

20 I claim:

1. In an ophthalmic mounting, a pair of lens rims, a bridge member extending between said rims and in engagement therewith, separate clamping members folded about the ends of said bridge and beneath the edges of said rims to hold the same in assembled relation, and recesses and integral projections on said members respectively interfitting to maintain said members against relative movement.

2. In an ophthalmic mounting, a pair of lens rims, a bridge member extending between said rims and in engagement therewith, and separate clamping members folded

35

about the ends of said bridge and beneath the edges of said rims to hold the same in assembled relation, said clamping members having upset pockets to receive the ends of said bridge member, said pockets and bridge member ends being shaped to interfit and prevent relative movement.

3. In an ophthalmic mounting, a pair of lens rims, a bridge member extending between said rims and in engagement therewith, separate clamping members folded about the ends of said bridge and beneath the edges of said rims to hold the same in assembled relation, said clamping members having pockets with projecting portions, to receive the ends of said bridge member, and said bridge member having notches in its ends to receive said projecting portions to hold the members against relative movement.

4. In an ophthalmic mounting, a pair of non-metallic rims, a bridge member of relatively hard spring metal stock having one end in engagement with each of said rims, and clamping members of relatively soft metal for embracing the ends of said bridge and said rims and holding the same in engagement, said clamping members having upset pockets to receive the ends of said bridge member, said pockets and bridge member ends being shaped to interfit in substantially the vertical plane of the bridge member and prevent relative movement.

JOHN FIELDING.
